CLAIM

The ornamental design for a set of partitions for a commercial aircraft passenger cabin, as shown and described.

DESCRIPTION

FIG. 1 is a front-left side perspective view of a set of partitions for a commercial aircraft passenger cabin according to my design;

FIG. 2 is a top plan view thereof;

FIG. 3 is a left side elevation view thereof;

FIG. 4 is a right side elevation view thereof;

FIG. 5 is a rear elevation view thereof;

FIG. 6 is a front elevation view thereof;

FIG. 7 is a front-left side perspective view of the set of partitions of FIG. 1, shown with commercial aircraft passenger cabin seats, ottomans and additional partitions;

FIG. 8 is a top plan view of the set of partitions, seats, ottomans, and additional partitions shown in FIG. 7;

FIG. 9 is a front-left side perspective view of the set of partitions of FIG. 1, shown in a commercial aircraft passenger cabin;

FIG. 10 is a front-left side perspective view of the set of partitions of FIG. 1, shown in another commercial aircraft passenger cabin; and,

FIG. 11 is a top plan view of the set of partitions and cabin as shown in FIG. 9.

No bottom plan view is included as no features of the claimed design are visible therein.

Throughout the Figures, the broken lines on the partitions represent the unclaimed boundaries of the claimed design, with the shaded areas being part of the claimed design and the non-shaded areas forming no part of the claimed design. The broken lines showing environment are for illustrative purposes only and form no part of the claimed design.

As shown in the Figures, both the design of the individual partitions and the partition arrangement (the positioning of each with respect to the others) are within the scope of the claimed design.
